By

Charles Worer
his Attorney.

UNITED STATES PATENT OFFICE.

FRED G. NIECE, OF CLEVELAND, OHIO, ASSIGNOR TO THE INTERNATIONAL HOLDING COMPANY, OF CLEVELAND, OHIO, A CORPORATION OF OHIO.

APPARATUS FOR TREATING HYDROCARBONS.

Application filed July 1, 1922. Serial No. 572,119.

To all whom it may concern:

Be it known that I, FRED G. NIECE, a citizen of the United States, residing at Cleveland, in the county of Cuyahoga and State of Ohio, have invented new and useful Improvements in Apparatus for Treating Hydrocarbons, of which the following is a specification.

This invention relates to improvements in apparatus for treating hydrocarbons, and more especially to an apparatus in which a hydrocarbon to be cracked is fed by an upright pipe or pipes which extend and discharge into a molten body penetrable by hydrocarbons and heated to but not vaporizable at the required hydrocarbon-cracking temperature and contained in a receptacle in which hydrocarbons are to be subjected to the heat of and within said molten body.

In the use of a receptacle supplied with said molten body into which discharge a stationary hydrocarbon-feeding pipe or pipes extending from above and into said molten body it has been found that, when the heating of said receptacle and contents are interrupted as required for an interruption in the operation of the apparatus preparatory to making repairs, or for any other reason such, for instance, as a temporary exhaustion or stoppage in the supply of hydrocarbon, said molten body cools and becomes a solid body by which said pipe or pipes are tightly embraced and, when said receptacle and contents are again being heated as required for a resumption of the operation of the apparatus, there may be such an abnormal rise in the pipe-embracing cooled and solidified material as to result in a detrimental, if not ruinous, buckling, crumpling or distortion of said pipe or pipes.

The primary object of this invention is to positively prevent said buckling, crumpling or distortion of said pipe or pipes.

Another object is to have said pipe or pipes movable endwise without interrupting the supply of hydrocarbon thereto.

Another object is to conduct hydrocarbon from a stationary pipe externally of the hereinbefore mentioned receptacle to said internal endwise movable pipe or pipes without interrupting communication between said external pipe and said internal pipe or pipes during endwise movement of said internal pipe or pipes, and to render the con-

struction of the connection between said external pipe and said internal pipe or pipes simple, durable and highly practical.

Another object is to have said internal pipe or pipes discharge into the hereinbefore mentioned molten body and capable of expansion and contraction endwise independently of the hereinbefore mentioned receptacle, and to have said pipe or pipes, without interfering with said expansion and contraction, placed in communication with a pipe employed in conducting hydrocarbon to be fed to said receptacle from a point externally of the receptacle.

Another object is to cause said hydrocarbon to be fed from said external pipe into a substantially vertical stationary tubular member formed internally of the upper end portion of said receptacle, to have the hereinbefore-mentioned endwise movable pipe or pipes connected to said stationary tubular member by a sleeve which embraces and is movable endwise of and extends below said stationary tubular member and participates in establishing communication between said stationary tubular member and said pipe or pipes, so that said pipe or pipes have not only a limited endwise movement but are expansible and contractible endwise independently of said stationary tubular member.

Another object is to insure lowering of said endwise movable pipe or pipes upon a rise of said pipe or pipes from their lowermost position.

With these objects in view, and to attain other objects hereinafter appearing, this invention consists in certain features of construction, and combinations and relative arrangements of parts, hereinafter described in this specification, pointed out in the claims, and illustrated in the accompanying drawings.

In said drawings, Figure 1 is a side elevation, largely in section and partly diagrammatic, of my improved apparatus. Fig. 2 shows a portion of Fig. 1 on a larger scale. Figs. 3 and 4 are horizontal sections taken along the line 3-3 and line 4-4 respectively in Fig. 2, looking upwardly. Fig. 5 is a horizontal section taken along the line 5-5 in Fig. 2, looking downwardly.

Referring to said drawings, A, in Fig. 1, indicates the casing of a heating furnace

comprising an oil-burner B the flames or fire 7 issuing from which, during the operation of the furnace, enter the combustion and heating chamber 8 through an aperture 9 in the furnace-front. Said chamber extends rearwardly from said aperture and thence upwardly, as at 10, and discharges at its upper end into a flue 11 communicating at its lower end, as at 12, with a stack 13. Surface 10 rounded by the portion 10 of said chamber is a hydrocarbon-cracking receptacle shown consisting of a steel base 15, a top steel section 16 and an intermediate section 17. The base 15 is secured in place in any approved manner, and the top section 16 is arranged above and externally of the furnace-casing A. The intermediate section 17 is formed by a vertical tube which is circular in cross-section and has suitable dimensions such, for instance, as a diameter of from ten to twelve inches and a height of from eight to twelve feet. Said tube forms the surrounding wall of the main portion of the hydrocarbon-cracking chamber, and the base 15 has a cavity 18 forming the lower end of said chamber. The tube 17 communicates at its upper end with the chamber 19 formed interiorly of the top section 16 and forming the upper end portion of the hydrocarbon-cracking chamber. Preferably adjacent ends of the base 15 and tube 17 are welded together, and adjacent ends of the top section 16 and tube 17 have external flanges 20 removably secured together, as at 21, by bolts and nuts. The chamber 19 in the top section 16 is closed at its upper end by a steel head 22 removably secured to the body of said section by bolts and nuts, as at 23. Preferably the chamber 19 measures in diameter at its lower end substantially the same as the internal diameter of the tube 17 and is diametrically larger above its lower end portion and shown provided with an outwardly and downwardly extending pipe 20 having a normally closed valve 26.

Within and centrally of the lower end portion of the hereinbefore mentioned hydrocarbon-cracking chamber is an inverted-cup-shaped member 27 of steel. Said member 27 is rigid with an upright tubular member 28 which is rigid at its lower end with the base 15 and discharges into the chamber 29 formed interiorly of the member 27 and communicates with a bore 30 formed in said base.

A pipe 31 for conducting fuel oil, or other liquid hydrocarbon to be treated, extends from above and into the portion 10 of the heating chamber to the base 15 to which said pipe is secured. Said pipe 31 discharges through the bore 30 into the tubular member 28. The pipe 31 is shown covered, from the base 15 to a point near the upper end of the portion 10 of the heating chamber, 60 with heat-resisting material such, for in-

stance, as asbestos 32. A diagrammatically illustrated oil-pump 33, arranged externally of the furnace, is interposed between the pipe 31 and a pipe 34 by which liquid hydrocarbon is supplied. Said pump is employed in forcing liquid hydrocarbon from the pipe 34 into the pipe 31 which has a diagrammatically illustrated check-valve 35 for preventing return of oil in said pipe.

A vapor-conducting pipe 36, forming the vapor-outlet of the hereinbefore mentioned hydrocarbon-cracking receptacle, communicates with the diametrically larger portion of the chamber 19 in the section 16 of said receptacle and is employed in conducting gases and vapors from said receptacle to a condenser (not shown).

The head 22 of the top section 16 of the hydrocarbon-cracking receptacle is provided, at its inner side and centrally, with a vertically downwardly projecting tubular member 38 which is therefore arranged in and centrally of the upper end portion of said receptacle. Said member 38 is therefore stationary and preferably circular in cross-section, as shown in Fig. 3, and adapted to receive hydrocarbon gases at its upper end and discharge at its lower end. Said member 38 is embraced or surrounded by a correspondingly vertically arranged steel sleeve or cylinder C which is movable endwise of and guided by said member 38 and spaced at its upper end downwardly from the upper end of and extends below said member 38 and has an integral head 40 at its lower end, and 41 indicates a chamber formed internally of said cylinder C between the head 40 and the lower end face of the member 38.

42 (see Fig. 1) indicates a pipe for supplying hydrocarbon gases and vapors which are obtained from any suitable source and include free hydrogen and unsaturated hydrocarbon compounds, and a diagrammatically illustrated gas-pump 43 is interposed between the pipe 42 and a pipe 45 which is connected by a union or coupling 47 to and communicates with a pipe 46 threaded into and centrally of the head 22. The pipe 45 discharges at the upper end of and into the tubular member 38.

The lower end portion of the member 38 (see Figs. 2 and 4) is provided, at its outer circumference, with vertically spaced annular grooves 50, and each groove 50 is engaged by a split resilient and expandable and contractible steel packing ring 51 snugly embraced by the sleeve or cylinder C and participating in the formation of a substantially fluid-tight joint between said cylinder and the member 38. The packing rings 51, and also the opposing vertical surfaces of the members 38 and C are lubricated in any approved manner as, for instance, by graphite.

As already hereinbefore indicated, the

sleeve or cylinder C surrounds and is movable endwise of the stationary tubular member 38 and is arranged with its head 40 arranged under the lower end face of said member 38, and spaced downwardly from said face in the lowermost position of said cylinder in the lowermost position of said cylinder and said cylinder is shown provided (see Figs. 1, 2 and 5) with a plurality of short 5 inclined pipe-sections 52 which communicate with the chamber 41 and are spaced circumferentially of the central portion of and extend downwardly and outwardly from said head. Each pipe-section 52 is connected and 10 placed in communication, by an elbow 53, with an upright pipe 55 arranged under the lower end of said pipe-section 52 and wholly internally of the hydrocarbon-cracking receptacle. Each pipe 55 (see Fig. 1) is loosely 15 seated, at its lower end, on the inverted-cup-shaped member 27 and has its lower end preferably formed as required to discharge laterally and inwardly. Obviously, therefore, the pipes and connected cylinder 55 20 are movable vertically or endwise, and the member 27 constitutes means for limiting descent of said pipes and connected cylinder.

The pipes 55 extend through a plurality 25 of vertically spaced downwardly flaring baffle-members D arranged between the top of 30 the furnace and the lower ends of said pipes. Each baffle-member D has a central hole or passage 57 extending vertically through the baffle-member. Preferably each baffle-member D is welded to and braces apart the 35 pipes 55.

Wherever required the joints between component parts of the apparatus are rendered 40 fluid-tight and capable of withstanding heat and strains to which said parts may be subjected, and in making said parts such metal or material as will withstand the heat and wear and tear to which said parts may be subjected is used.

45 The hydrocarbon-cracking receptacle is supplied with a low-melting metal or material such, for instance, as lead which has a melting point lower than the temperature required to be established and maintained in 50 said receptacle during the operation of the apparatus and is readily penetrable, in a molten condition, by hydrocarbon fluids and not vaporizable at said temperature. E, in Fig. 1, indicates a molten column or body 55 resulting from the melting of a mass of small pieces of solid lead supplied to said receptacle preferably preparatory to the introduction of the pipes 55 and connected sleeve or cylinder C and baffle-members D 60 into said receptacle, and of course said pipes and connected cylinder and baffle-members are lowered into said receptacle preparatory to the application of the head 22. Preferably such a quantity of low-melting metal is 65 introduced into the hydrocarbon-cracking

chamber that the surface of the molten body E, during the subjection of hydrocarbons to the heat of and within said molten body, is below the upper extremity of the tube 17 and above the uppermost baffle-member D and 70 therefore below the upper ends of the pipes 55. The base 15 of the hydrocarbon-cracking chamber is shown provided with a drain-pipe 58 through which, upon opening a normally closed valve 59 with which said pipe is provided, the molten metal may be 75 drained from said chamber.

The hereinbefore mentioned furnace is operated as required to heat the hydrocarbon-cracking receptacle and contents to and 80 maintain them at a hydrocarbon-cracking temperature varying from about four hundred to about seven hundred and fifty degrees centigrade according to the nature of the liquid hydrocarbon to be treated, and 85 the molten body E is therefore maintained at said temperature during the operation of the apparatus.

By operating the oil-pump 33 and gas-pump 43 liquid hydrocarbon is forced 90 through the pipe 31, bore 30, tubular member 28 and chamber 29 in the member 27 into the lower portion of the molten body E, and hydrocarbon gases and vapors are forced to and through the pipe 46 and tubular member 38 to and through the pipes 55 95 into said portion of said molten body and discharged into the molten body between the member 27 and the lowermost of the baffle-members D, and I would here remark that 100 preferably the member 27 and the member 38 and cylinder C are substantially in line vertically.

By the hereinbefore described construction and relative arrangement of the parts 105 it will be observed that the pipes 55 have a limited range of movement vertically or endwise and extend into the molten body E from a point spaced upwardly from the level or surface of said molten body, that the inverted-cup-shaped member 27 forms a seat for said pipes 55 in the lowermost position of the pipes, that the sleeve or cylinder C is adequately spaced at its upper extremity 110 downwardly from the upper extremity of the stationary tubular member 38 in the lowermost position of the pipes 55 and embraces or surrounds said member 38 in any position of the cylinder and connected pipes 55, that the head 40 of said cylinder is 115 adequately spaced downwardly from the lower end face of the member 38 in the lowermost position of the pipes 55, that the packing rings 51 are embraced by said cylinder 120 in any position of the cylinder and connected pipes 55, that said cylinder constitutes means establishing and maintaining communication between the member 38 and the pipes 55 in any position and during endwise movement of said pipes and connected 125 130

cylinder, and that therefore the connection between the pipe 46 and the pipes 55 is such that the supply of vapors and gases from said pipe 46 to the pipes 55 is not interrupted during the operation of the apparatus.

It will be observed that the movability of the pipes 55 and connected sleeve or cylinder C in the direction of the head 22 prevents distortion of or injury to said pipes during the presence in the receptacle of any force or agency having a tendency to actuate said pipes in said direction, that the attachment of said pipes 55 only to said cylinder permits expansion of said pipes endwise independently of or a greater distance than the expansion endwise of the stationary tubular member 38 and the receptacle provided with said member 38 without distortion of or injury to the pipes, and that expansion and contraction of said pipes 55 independently of said receptacle or its member 38 do not interfere with the maintenance of communication between each of said pipes 25 and the hydrocarbon-feeding pipe 46.

What I claim is—

1. Hydrocarbon-treating apparatus comprising a closed receptacle which has a vapor-outlet, an upright stationary tubular member at the upper portion of said receptacle, a molten body contained in said receptacle and penetrable by hydrocarbons and not vaporizable at the required hydrocarbon-cracking temperature, means for supplying hydrocarbon gases under pressure to said stationary tubular member, an upright cylinder arranged internally of the aforesaid receptacle and connected to and movable endwise of and communicating with the aforesaid stationary tubular member, and an upright feed-pipe arranged internally of said receptacle and discharging into the molten body and connected to and movable with said cylinder and in communication with said stationary tubular member in any position of said pipe and connected cylinder.

2. Hydrocarbon-treating apparatus comprising a hydrocarbon-cracking receptacle which has a vapor-outlet, a molten body contained in said receptacle and penetrable by hydrocarbons and not vaporizable at the desired hydrocarbon-cracking temperature, an endwise movable upright cylinder arranged at the upper portion of said hydrocarbon-cracking receptacle, means for supplying fluid under pressure into said cylinder from a point externally of the molten-body-containing receptacle, a feed-pipe connected to and movable with said cylinder, and means independent of said pipe and connected cylinder for supplying hydrocarbons into the molten body, said pipe extending into and communicating with the molten body.

3. Hydrocarbon-treating apparatus comprising a hydrocarbon-cracking receptacle

which has a vapor-outlet, a head arranged to constitute a closure for the upper end of said receptacle, a substantially vertical tubular member rigid with said head, a molten body contained in the aforesaid receptacle and penetrable by hydrocarbons and not vaporizable at the required hydrocarbon-cracking temperature, means for supplying a hydrocarbon gas under pressure to said stationary tubular member from a point externally of said receptacle, a cylinder connected to and slidably endwise of said stationary tubular member, and an upright pipe arranged internally of said receptacle and connected to said cylinder, said pipe and connected cylinder having a limited endwise movement, and said pipe being adapted to be employed in feeding the hydrocarbon gas received thereby into the aforesaid molten body and communicating with the aforesaid stationary tubular member in any position of the pipe and connected cylinder.

4. Hydrocarbon-treating apparatus comprising a hydrocarbon-cracking receptacle which has a vapor-outlet, a molten body contained in said receptacle and penetrable by hydrocarbons and not vaporizable at the required hydrocarbon-cracking temperature, an upright, stationary tubular member at the upper end of said receptacle, means for conducting hydrocarbon gas to said stationary tubular member from a point externally of said receptacle, a cylinder slidably embracing said stationary tubular member and having a head arranged under the lower end face of said stationary tubular member, a pipe internally of the aforesaid receptacle and attached to said head of said cylinder, said pipe and connected cylinder having a limited endwise movement, the aforesaid stationary tubular member being surrounded by said cylinder in any position of said pipe and connected cylinder, and said pipe being in communication at its upper end with said stationary tubular member in any position of the pipe and connected cylinder and extending downwardly below the aforesaid head of said cylinder and communicating with the aforesaid molten body in any position of said pipe and connected cylinder.

5. Hydrocarbon-treating apparatus comprising a closed receptacle which has a vapor-outlet, a molten body contained in said receptacle and penetrable by hydrocarbons and not vaporizable at the required hydrocarbon-cracking temperature, an upright pipe adapted to be employed in feeding hydrocarbon gas to said molten body, said pipe extending into and movable endwise in said molten body, a pipe externally of the receptacle and adapted to be employed in supplying hydrocarbon gas to said endwise movable pipe, means for establishing and maintaining communication be-

- tween said pipes during endwise movement and in any position of said endwise movable pipe, a member arranged to form a seat for said endwise movable pipe in the lowermost position of the pipe and having an interior chamber which is in communication with the molten body, and means for supplying hydrocarbons to said chamber.
6. Apparatus of the character indicated comprising a closed receptacle which has a vapor-outlet, a molten body contained in said receptacle and penetrable by hydrocarbons and not vaporizable at the desired hydrocarbon-cracking temperature, an upright stationary tubular member at the upper portion of said receptacle, means for supplying hydrocarbon gas to said tubular member from a point externally of said receptacle, an endwise movable upright pipe internally of said receptacle, means whereby communication between said stationary tubular member and said movable pipe is established in any position of said pipe, a stationary inverted-cup-shaped member internally of the lower end portion of said receptacle, and means for supplying hydrocarbons to the chamber formed interiorly of said inverted-cup-shaped member, said inverted-cup-shaped member forming a seat for the aforesaid movable pipe in the lowermost position of the pipe.
7. Hydrocarbon-treating apparatus comprising a hydrocarbon-cracking receptacle which has a vapor-outlet, a molten body contained in said receptacle and penetrable by hydrocarbons and not vaporizable at the desired hydrocarbon-cracking temperature, an endwise movable upright pipe arranged internally of said receptacle and communicating with said molten body; a pipe arranged to supply hydrocarbon gas to said endwise movable pipe from a point externally of said receptacle, means for supplying hydrocarbon gas under pressure through the second-mentioned pipe into the first-mentioned and endwise movable pipe, and means for establishing and maintaining communication between said pipes during endwise movement and in any position of said endwise movable pipe.
8. Hydrocarbon-treating apparatus comprising a hydrocarbon-cracking receptacle which has a vapor-outlet, a molten body contained in said receptacle and penetrable by hydrocarbons and not vaporizable at the required hydrocarbon-cracking temperature, a substantially vertical stationary tubular member arranged centrally of the upper end portion of the receptacle, means for supplying fluid under pressure to said stationary tubular member, a cylinder slidably connected to and movable endwise of said stationary tubular member, an upright feed-pipe arranged internally of said receptacle and attached to said cylinder and extending from the cylinder downwardly and discharging into the lower portion of the molten body, a member disposed to form a seat for said feed-pipe in the lowermost position of said cylinder and arranged substantially in line vertically with said cylinder and having an interior chamber discharging into the molten body, and means for supplying a hydrocarbon to said chamber, the aforesaid stationary tubular member being in communication with the aforesaid feed-pipe in any position of said pipe and connected cylinder.
9. Hydrocarbon-treating apparatus comprising a hydrocarbon-cracking receptacle which has a vapor-outlet, a molten body contained in said receptacle and penetrable by hydrocarbons and not vaporizable at the desired hydrocarbon-cracking temperature, an upright stationary tubular member at the upper end portion of said receptacle, an endwise movable pipe arranged internally of said receptacle and extending into and communicating with the molten body, an interiorly chambered member arranged to form a connection between and communicating with said pipe and the aforesaid stationary tubular member, said interiorly chambered connection-forming member being adapted to be actuated with and during endwise movement of said pipe, and means for supplying hydrocarbons into the molten body through said stationary tubular member, connected interiorly chambered member, and connected pipe.

In testimony whereof, I sign the foregoing specification, this 17th day of June, 1922.

FRED G. NIECE.
